(57) **CLAIM**

The ornamental design for a sand brush as shown.

DESCRIPTION

FIG. 1 is a top perspective view of a sand brush showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is rear elevational view thereof; and,

FIG. 7 is front elevational view thereof.

In the drawings, the broken lines are for the purpose of illustrating portions of the sand brush that form no part of the claimed design.
